UNITED STATES PATENT OFFICE.

SAMUEL R. GARRISON, OF DENNISVILLE, NEW JERSEY, ASSIGNOR OF ONE-HALF TO A. ELTON HOLMES, OF SAME PLACE.

SHOE-LAST AND STANDARD.

SPECIFICATION forming part of Letters Patent No. 373,974, dated November 29, 1887.

Application filed April 7, 1887. Serial No. 233,993. (No model.)

To all whom it may concern:

Be it known that I, SAMUEL R. GARRISON, a citizen of the United States, and a resident of Dennisville, Cape May county, New Jersey, have invented an Improvement in Combined Shoe-Lasts and Anvils, of which the following is a full, clear, and exact description, reference being had to the annexed drawings, making part hereof.

10 My invention relates to improvements in boot and shoe lasts when the same are used in conjunction with a standard, upon which they are set to form an anvil.

The lower lip, J, of tongue I rests against 15 the front of standard F, forming a stay or stop, as described.

The nature of my invention will fully appear from the following specification and claims.

In the drawings, Figure 1 is a vertical longitudinal section of my device; Fig. 2, a front elevation of the same; Fig. 3, a broken side elevation.

A is the last, having a downwardly-projecting tongue, I, which is provided with an inclined open slot, B, to receive the pivot C, which is set between the ears D E.

F is a standard, of which the ears D E form an integral part. Its lower end, G, sets in a socket-piece, H, which may be screwed to the 30 floor, bench, or other suitable support. Tongue I is provided with a lower lip, J, which, with the shoulders K K, acts as a check or stop to hold the last firmly in place when in use. Supplemental inside shoulders, L L, also assist in 35 this purpose.

Ear D is rounded at one corner, M, ear E being similarly constructed. The inner parts, N N, of ears D E, which form rests or supports for shoulders L L, are also each rounded 40 at one corner. (See O in dotted lines, Fig. 1.) Tongue I is also provided with a rounded corner, P. These rounded corners permit the last to be turned on its pivot when it is desired to remove it, or to throw it up at an 45 angle to permit a long shoe or boot to be pushed farther down upon it to enable the point of the last to reach the toe of the shoe or boot.

When a shoe or boot is being pounded dur-

ing the insertion of pegs or nails, the inclination of slot B will prevent lateral or vertical movement or vibration of the last and hold it firmly fixed. The last can be easily detached for insertion in the shoe or boot, and can then be set on the standard F; or it can be set on the standard, turned partially upward, and a 55 boot-leg can be pulled down over it and the standard, and when the last has entered the foot it may be turned down to the position shown in Fig. 1. If desired, the standard may be removed from socket-pin H, pushed into 60 the boot-leg connected with the last in the foot of the boot, and then may be reset in socket-piece H. By the use of my device lasts of various sizes and forms may be used alternately upon the same standard. One can be removed 65 and replaced by another at pleasure.

The tongue I may project upward from standard F, and the inclined slot B would then be from the middle of the tongue toward its upper edge, and the ears D E would be attached to the last, projecting downward, with the pivot C between them. In other words, these parts may simply be reversed and accomplish about the same results as with the present arrangement. 75

What I claim as new is—

1. The combination of standard F, provided with ears D E and pivot C, and last A, having a tongue, I, provided with an open slot, B, to receive the pivot C, substantially as and for the purpose described. 80

2. The combination of standard F, provided with ears D E and pivot C, and detachable last A, having a tongue, I, provided with an open slot, B, to receive the pivot C, the standard 85 F being detachably set in a socket-piece, H, substantially as and for the purpose described.

3. The combination of standard F, provided with ears D E, each having a rounded corner, M, and pivot C, detachable last A, having a 90 tongue, I, rounded at one corner, P, provided with an open slot, B, to receive pivot C, and shoulders K K, substantially as and for the purpose described.

4. The combination of standard F, provided 95 with ears D E, each having a rounded corner,

M, and pivot C, detachable last A, having a tongue, I, rounded at one corner, P, provided with an open slot, B, to receive pivot C, and a lower lip, J, substantially as and for the purpose described.

5 5. The combination of standard F, provided with ears D E and pivot C, and last A, hav-

ing tongue I, secured in place by said pivot and provided with the lip J, substantially as and for the purpose described.

SAMUEL R. GARRISON.
